PREPARATION OF FLUOROCARBON PHOSPHINES

Anton B. Burg and Walter Mahler, Los Angeles, Calif., assignors, by mesne assignments, to American Potash & Chemical Corporation, a corporation of Delaware

No Drawing. Application June 7, 1957
Serial No. 664,183

9 Claims. (Cl. 260—606.5)

This invention relates in general to the preparation of fluoroalkyl phosphines and more particularly to a method by means of which bis(fluoroalkyl) phosphorous halides may be treated with mercury in the presence of protonic, non-oxidizing acids, to produce alkyl phosphines.

The conventional manner in which fluoroalkyl phosphines of the type $(CF_3)_2PH$ are prepared is by the catalytic reduction of fluorocarbon phosphorous iodides by hydrogen. This is the method of Bennett, Emeléus and Haszeldine, reported in J. Chem. Soc., 1954, 3901. The method is fairly satisfactory where only small quantities of the product are desired, but difficulties are still presented in that the product is not readily purified, quantities of HF, HI and PH_3 being present.

It is therefore an object of this invention to provide for the preparation of fluorocarbon phosphines by a method which does not involve catalytic reduction of fluorocarbon phosphorous halides.

A further object of this invention is to provide a method which can be readily practiced at room temperature and which is capable of yielding fluorocarbon phosphines in good quantity in a relatively short period of time.

Broadly, it has been found that fluorocarbon phosphines such as $(CF_3)_2PH$ may be formed by the action of a metal such as mercury on a fluorocarbon phosphorous halide of the type such as $(CF_3)_2PX$, where X represents a halogen, in the presence of protonic acids lacking any oxidizing power of a nature which would interfere with the desired result.

More particularly, it has been found that reactions of the type:

are suitable for the preparation of long or short chain fluorocarbon phosphines. As is apparent from the above equation, the method of this invention does not involve the formation and use of H_2 , but rather the removal of a halogen followed by replacement by H^+ .

More particularly, it has been found that fluorocarbon phosphorous halides, and especially the iodides, may be reacted with mercury in the presence of protonic, non-oxidizing acid so as to yield fluorocarbon phosphines. A preferred embodiment of the invention involves the use of bis(trifluoromethyl) phosphorous iodide with mercury in the presence of HCl, the reaction taking place in a closed apparatus with a stoichiometric excess of the acid and an adequate pool of mercury, the ingredients being shaken for an hour or less at room temperature. Where it is desired to obtain a faster reaction, the temperature may be raised to as high as 100° C., or even somewhat higher if desired. The volatile product obtained will contain the fluorocarbon phosphine which may be separated from P-P linked products by distillation methods.

As set out earlier, either long or short chain fluorocarbon phosphines may be prepared. A wide variety of metals other than mercury are suitable, a requirement being that they have a good affinity for halogens. Of

2

course, mercury, being a liquid, is most convenient since the reaction may be encouraged by shaking together the various reactants. Any of a variety of non-oxidizing acids may be used, those set forth in the examples which follow giving some idea as to the wide range which are suitable. It is even possible to use water as the proton source, but because of hydrolytic side reactions somewhat more acid materials are preferred.

In a preferred embodiment of this invention wherein $(CF_3)_2PI$ and HCl are reacted with mercury, a good yield of $(CF_3)_2PH$ and $P_2(CF_3)_4$ is obtained. However, this reaction produces a certain amount of $(CF_3)_2PCl$ which may readily be removed by pure water hydrolysis. The pure $(CF_3)_2PH$ finally obtained generally appears in the yield of about 35% of the original $(CF_3)_2PI$. It is also possible first to treat the $(CF_3)_2PI$ or other halide with mercury to form a solid residue. This material is then treated with the acid. For example, where HCl is used to treat the solid residue obtained from the reaction of $(CF_3)_2PI$ and mercury, the product $(CF_3)_2PH$ in a yield amounting to 5% of the original $(CF_3)_2PI$ has been obtained. This demonstrates the presence of the linkage $Hg—P(CF_3)_2$ in the intermediate product.

It is also somewhat more convenient simply to prepare the $(CF_3)_2PH$ by using H_3PO_4 or CF_3COOH as the acid instead of HCl, since, in this fashion, the formation of $(CF_3)_2PCl$ is avoided. Yields again are in the neighborhood of 35%.

Examples illustrating the practice of this invention are set forth below but are not to be construed as imposing limitations on the scope of the invention other than as are set forth in the appended claims.

Example I

35 Samples of $(CF_3)_2PI$ (0.414 g.) and anhydrous HCl (0.0912 g.) were brought together in a closed flask containing 50 g. of mercury and shaken for one hour at room temperature. The volatile products were distilled off and separated by means of a high-vacuum distillation apparatus. One by-product was 0.068 g. of the previously known substance $P_2(CF_3)_4$, which could be identified by its characteristic vapor tensions and molecular weight. Another by-product was $(CF_3)_2PCl$ (0.105 g.), which was destroyed by the action of pure water. The yield of pure $(CF_3)_2PH$ was 0.083 g., or 35% of the original $(CF_3)_2P$ units. It was identified by its characteristic vapor tensions and molecular weight.

Example II

50 A 1.865 g. sample of $(CF_3)_2PI$ was shaken for 30 minutes with 10 g. of 85% H_3PO_4 and 100 g. of mercury in a closed container at room temperature. After purification by distillation to remove by-products which included fluorocarbonoxy-phosphines, the yield of $(CF_3)_2PH$ was determined as 0.357 g. (33% yield).

Example III

60 A 3.85 g. sample of $(CF_3)_2PI$ was shaken with 10 g. of CF_3COOH and 100 g. of mercury in a closed container for 20 minutes at room temperature. The yield of pure $(CF_3)_2PH$ (which was identified by its characteristic physical properties and nuclear-magnetic-resonance spectrum) amounted to 0.774 g., or 35%.

Example IV

65 2.5 millimol HCl and 1.4 mmol $(CF_3)_2PI$ were brought into a flask containing 300 g. mercury and shaken together for 2 hours. The volatile products were fractionated in high vacuum and consisted of .3 mmol $(CF_3)_4P_2$ and a mixture of $(CF_3)_2PH$ and $(CF_3)_2PCl$. This mixture was resolved by destruction of the

$(CF_3)_2PCl$ by a neutral water hydrolysis and .5 mmol $(CF_3)_2PH$ was obtained pure, representing a yield of 35%.

Example V

6.3 mmol $(CF_3)_2PI$ were brought into a flask containing 100 g. Hg and 10 g. of 85% H_3PO_4 (tech), shaken for 30 minutes and the products fractionated to give 2.2 millimols (35% yield) of $(CF_3)_2PH$. Other products of this reaction were fluorocarbon phosphines containing oxygen such as $(CF_3)_2P(O)H$.

Example VI

12.9 mmol $(CF_3)_2PI$ were brought into a flask containing 250 g. Hg and 20 g. CF_3COOH and shaken for 1 hour. Fractionation delivered 4.3 mmol of $(CF_3)_2PH$, representing a 33% yield.

A variety of the fluorocarbon phosphorous halides used as reactants are known. A preferred method for their preparation is that set forth in the Journal of the American Chemical Society, 79, 247 (1957), "The Synthesis of Fluorocarbon Phosphorous Iodides." The method set out there may be applied with minor modifications to the preparation of other halides.

As can be seen from the foregoing, it is possible by following the teachings of this invention to produce fluorocarbon phosphines in a fashion which enables the production of the desired product in fairly large yields. These products may be treated with diborane in the fashion set forth in the co-pending application, Serial No. 663,623, filed June 5, 1957, relating to "Fluorocarbon phosphinoborines." As set out in that application, the products which are obtained by this diboranefluorocarbon phosphine reaction are polymeric materials having high thermal and chemical resistance which can be used as hydraulic fluids under high temperature conditions. The products of the instant invention, therefore, are suitable as intermediates in the preparation of these new polymers.

Obviously many modifications and variations of the invention as hereinbefore set forth may be made without departing from the spirit and scope thereof, and therefore only such limitations should be imposed as are indicated in the appended claims.

We claim:

1. A process for the preparation of fluorocarbon phosphines which comprises: treating $(RCF_2)_2PX$ where R is from the group consisting of lower alkyl and fluorine and X is iodine with mercury in the presence of a member from the group consisting of water and a protonic, non-oxidizing acid and separating said fluorocarbon phosphine so formed from the reaction mixture.

2. The process of claim 1 wherein the acid is hydrochloric acid.

3. The process of claim 1 wherein the acid is phosphoric acid.

4. The process of claim 1 wherein the acid is CF_3COOH .

5. The process for the preparation of trifluoromethyl phosphine comprising: treating $(CF_3)_2PI$ with mercury in the presence of a protonic, non-oxidizing acid and separating the fluorocarbon phosphine so formed from the reaction mixture by fractional distillation.

6. The process of claim 5 wherein the acid material is hydrochloric acid.

7. The process of claim 5 wherein the acid is phosphoric acid.

8. The process of claim 5 wherein the acid is CF_3COOH .

9. The process of claim 5 wherein the acid material is water.
